(57) **CLAIM**

The ornamental design for a cosmetic container, as shown and described.

DESCRIPTION

FIG. 1 is a perspective view showing our new design for a cosmetic container with the cap element removed to disclose the underlying parts;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof; and,

FIG. 8 is a perspective view showing the design in its capped state.

The broken lines are included for the purpose of illustrating a portion of the cosmetic container that forms no part of the claimed design.
